FUEL FEEDING SYSTEM FOR MOTOR VEHICLES

Original Filed May 25, 1925

UNITED STATES PATENT OFFICE

FRANK H. HEITGER, OF FLINT, MICHIGAN, ASSIGNOR TO MARVEL CARBURETER COMPANY, OF FLINT, MICHIGAN, A CORPORATION OF INDIANA

FUEL FEEDING SYSTEM FOR MOTOR VEHICLES

Application filed May 25, 1925, Serial No. 32,648. Renewed October 20, 1931.

This invention relates to certain new and useful improvements in fuel feeding systems for motor vehicles and is a companion application of my application filed even date here-
5 with, the object being to provide novel means for operating the piston of the pump so that the piston can be operated in such a manner that the operating means is free to move in-
dependent of the piston whereby the move-
10 ment of the piston is controlled by the con-
sumption of fuel.

Another and further object of the invention is to provide a fuel feeding system in which the pump is provided with a collect-
15 ing chamber for collecting the leakage past the piston whereby it can be returned to the intake of the pump.

Other and further objects and advantages of the invention will be hereinafter set forth
20 and the novel features thereof defined by the appended claims.

In the drawings,

Figure 1 is a vertical section through part
25 of the system, part being shown in elevation;

Figure 2 is a detail vertical section through the upper portion of the pump showing a slightly modified form.

In the drawings 1 indicates a charge forming device which is provided with a fuel bowl 2 in which is mounted a float 3 carrying a valve 4 for controlling the inlet 5 thereof, which is of the usual construction now in use so as to maintain a constant level within the
30 float chamber of the charge forming device.

My improved construction of pump comprises a pump barrel 6 having an outlet 7 controlled by a spring pressed check valve 8 which is connected by a pipe 9 to the inlet
35 of the bowl 2 of the charge forming device. The pump barrel is provided with an inlet 10 controlled by a spring pressed valve 11, said inlet being adapted to be connected to a low level tank as shown in my companion
40 application so that fuel can be drawn from the low level tank and forced directly to the bowl of the charge forming device.

The pump barrel is enlarged to form a chamber 12 from which extends a passage 13 to a collecting chamber 14 in which is mount-

ed a float 15 having a valve 16 controlling the outlet 17. The outlet is also controlled by spring pressed valve 18 and is in communication with the bottom of the pump barrel by branch 19, the tension of the spring for holding the valve 18 in closed position being less than the tension of the spring for holding the valve 11 seated so that when fuel is in the collecting chamber 14, it will be drawn into the pump barrel until consumed when the valve 11 will open on the suction stroke of the piston so as to draw fuel from the low level tank not shown.

The float carries a rod 20 working through a plug 21 forming a closure for the upper end of the collecting chamber 14, said closure being provided with a vent 22.

Slidably mounted within the pump barrel 6 is a piston 23 annularly reduced as shown at 24 to form in conjunction with the chamber 12 an annular chamber in which the liquid which leaks by the piston is collected and flows by gravity into the collecting chamber 14. The upper end of the piston is provided with a vertical bore 25 enlarged as shown at 26, said enlargement being threaded to receive a plug 27 through which extends a piston 28 provided with a head 29 at its lower end working in the bore 25. Said piston extends upwardly through a bearing 30 formed in a cap 31 forming a closure for the upper end of the barrel and is pivotally connected at 32 to a link 33 which is pivotally connected to a wrist pin 34 carried by crank disc 35 adapted to be driven by a revolving part of the internal combustion engine to which the fuel system is applied or any other source of power whereby a rotary motion will be converted to the crank disc 35 in order to reciprocate the piston.

Arranged in the upper end of the pump barrel above the piston is a coil spring 36 which is adapted to be compressed when the piston 25 is drawn upwardly on the suction stroke so that when it is released by the piston rod which is loosely connected through the medium of the bore and plug, the spring will force the piston down to discharge the liquid drawn within the barrel.

The construction shown is for the purpose

of forming a sliding or loose connection between the piston rod and piston so that if the pressure exerted on the outlet of the pump barrel is greater than the pressure exerted by the spring and the weight of the piston can remain in a raised position and the piston rod can operate back and forth in the bore 25 through its loose connection without operating the piston to force fuel out of the barrel 10 and in constructing a fuel feeding system in accordance with my invention, the float in the fuel bowl 2 of the charge forming device is so constructed that it over-balances the tension of the spring 36 and the weight of 15 the piston 23 and maintains the valve in a closed position as long as the fuel within the bowl is maintained at a predetermined level, whereby the outlet of the pump barrel remains closed so that the piston fails to reciprocate with the piston rod and is held in a raised position on the suction stroke until the pressure is reduced or until the liquid under the piston has leaked past the piston into the collecting chamber 14. As the float 15 20 in the collecting chamber closes the outlet of the collecting chamber until the liquid therein has reached a predetermined level, the pump does not begin to draw fuel from the collecting chamber until the float 15 25 30 raises to open the outlet valve.

In the operation of the fuel feeding system as shown when the piston is reciprocated or drawn upwardly by the piston rod, fuel is either drawn from the collecting chamber 14 35 or from the low level tank through the inlet 10 and as the piston rod has raised the piston upwardly against the tension of the spring, when the piston rod starts downwardly the piston will follow the piston rod 40 so long as the liquid within the bowl of the carburetor is below a predetermined level and just as soon as the liquid supply to the bowl raises above this predetermined level, the pressure exerted by the float 3 closes the 45 inlet to the bowl and the back pressure which is sufficient to overcome the tension of the spring and the weight of the piston prevents the piston from moving downwardly and through its loose connection with the piston rod, the piston rod continues to reciprocate 50 back and forth without operating the piston and of course, the pump fails to raise the fuel from the low level tank or from the receiving chamber.

55 When in this position the fluid under the piston gradually leaks by the piston into the collecting chamber and the piston slowly falls until it is again picked up by the piston rod 60 and raised and starts the pump to operate again and the operation of the pump being determined by the consumption of fuel by the charge forming device, as by the construction of connecting the piston rod loosely 65 to the piston, the piston rod continues to

reciprocate while the piston remains stationary.

In the modification shown in Figure 2, the pump barrel 40 carries a cap 41 at its upper end provided with a slot 42 through which extends a piston rod 43 which is pivotally mounted on a wrist pin 44 of the crank disc 45, said piston rod being provided with a spherical head 46 which is loosely mounted in a bore 47 formed in the piston 48, said rod working through a plug 49 carried by the piston so as to form a loose or sliding connection between the piston rod and piston, whereby the piston rod is allowed to reciprocate back and forth without forcing the piston downwardly when the back pressure is greater than the pressure exerted by the spring 50 disposed above the piston 48.

From the foregoing description it will be seen that I have provided a fuel pump employing a reciprocating piston operated by mechanical means through a piston rod which has a sliding connection with the piston so as to allow the piston to remain at its end of the suction stroke when the back pressure is sufficient to overcome the spring employed for forcing the piston down to discharge the liquid from the barrel beneath the same, in connection with a collecting chamber which collects the fuel leaking past the piston so that it can be drawn back into the pump barrel.

By this particular construction of pump with the piston loosely connected to its operating means, the movement of the piston is entirely controlled by the consumption of fuel as the piston is free to move independently of the operating means so that if only a small amount of fuel is being consumed, the piston may only move a slight distance or a short stroke on each revolution of the operating means and the distance of travel of the piston is determined by the consumption of fuel, as if the discharge from the pump is restricted, the piston will not follow the head on its downward stroke and as the fuel is consumed, the spring forces the piston downward and it is again picked up by the operating means so that the movement of the piston is entirely controlled by the consumption of fuel so that an ample supply of fuel is supplied to the charge forming device at all times without an over-supply.

What I claim is:

1. A pumping mechanism for fuel feeding systems comprising a pump barrel having a slidably mounted piston, a spring for moving said piston to discharge fuel from said pump and a piston rod slidably mounted in said piston for moving said piston on the suction stroke for compressing said spring, the movement of said piston being controlled by the consumption of fuel.

2. A pumping mechanism for fuel feeding systems for motor vehicles comprising a

- pump barrel, a piston slidably mounted in said pump barrel, a spring disposed above said piston within said barrel, said piston being provided with a vertical bore, an apertured plug for closing said bore and a piston rod passing through the aperture of said plug having a head working in said bore forming a loose connection between said piston and said piston rod.
- 10 3. A pumping mechanism for fuel feeding systems for internal combustion engines comprising a vertically disposed pumping barrel having a valve controlled inlet and outlet, a piston slidably mounted in said barrel, operating means for said piston, said piston having a sliding connection with said operating means and a spring disposed in said barrel above said piston for forcing said piston downwardly when released by said operating means.
